UNITED STATES PATENT OFFICE

JOSEPH E. WOOD, OF CHICAGO, ILLINOIS, ASSIGNOR TO THE DEARBORN COMPANY, OF CHICAGO, ILLINOIS, A CORPORATION OF ILLINOIS

TABLE

Application filed May 10, 1929. Serial No. 361,939.

My invention relates to improvements in tables and particularly card tables having legs which fold within the confines of the table frame.

The object of my invention is to provide a novel structure for supporting the folding legs entirely from the frame independently of the top of the table.

Another object is to provide a folding leg structure having all of the parts assembled on a supporting member which can be fastened to the table frame as a unit.

A further object is to provide an improved folding leg structure for tables which will be rigid and substantial with respect to the table without the use of exposed braces in open position, which can be readily and easily folded within the table frame, and which will be inexpensive to manufacture.

A further object is to provide an improved hinge structure permitting the legs to be folded and novel locking means for holding the legs in open or table supporting position.

Other objects of my invention will appear hereinafter.

Referring to the accompanying drawings.

Fig. 1 is a section of one corner of a card table showing in perspective the folding leg unit fastened in position within the corner of the table frame;

Fig. 2 is a sectional view on the line 2—2 of Fig. 4;

Fig. 3 is a sectional view on the line 3—3 of Fig. 4; and

Fig. 4 is a bottom plan view of the corner portion of the table and folding leg unit, with the leg itself in section.

The drawings illustrate one corner portion of a table and the folding leg structure associated with that corner portion, but it is understood, of course, that this structure is duplicated in all the other corners of the table so that all of the legs may be folded within the frame. Card tables are generally

made as light in weight as possible consistent with proper strength for the purpose, and the strengthen and rigidity in this type of table is principally in the frame. The top board A of a card table is generally made as thin and light in weight as possible. This top

board is supported around its edges by the frame members B and is usually covered with felt or a suitable fabric C to finish off the top surface of the table. The top board A is set in depressed shoulders 1 in the upper edge of the frame to finish off this edge, and glued in position. In addition to this small cleats 2 are distributed around the top adjacent the frame members and glued to the under surface of the top board. These cleats are secured by nails or screws 3 to the inside of the frame members. A cleat 2' is also preferably placed in each corner of the frame, Fig. 4. The frame B is composed of wooden strips arranged in rectangular relation and rigidly secured at their ends by mitering and gluing to form the joints at the corners of the frame.

I provide supporting plates or members 5 in the corners of the frame. These corner plates are triangular in shape with two sides at right angles to each other to fit the corner of the frame, and a diagonal side connection extending between the ends of the two right angled sides. This supporting member is

preferably made as a flat plate with flanges 6 turned at right angles to the plane of the plate to provide means by which the supporting plate may be secured to the table frame. The flanges also serve to strengthen the plate against bending. The supporting member is

placed in the corner of the frame with its top surface substantially in the plane of the shoulders 2 so that it will support the corner portions of the top board. It is secured in place by means of the screws 7 passing through the flanges 6 and into the frame members. The supporting plate 5 is preferably inexpensively made as a metal stamping. The corner of the supporting member 5 is cut out to provide a space for the corner cleats 2'. The edges of these cutout portions are also turned at right angles to form flanges 6' for strengthening the supporting plate.

A socket or channel member 10, for the leg 11 is mounted on the supporting member 5. This socket member is preferably rectangular to conform to the rectangular upper end of the leg, and is preferably made as a metal stamping with outstanding flanges 12 at right

100

angles to its walls 10 and 10'. The flanges are preferably riveted at 13 to the supporting member. The socket is disposed with its longitudinal axis at right angles to the top of the table, and is deep enough to embrace a sufficient portion of the length of the leg to brace the leg in rigid relation to the supporting member 5 when the leg is in open position. One side of the socket member is open and faces in the direction of the side member of the frame to permit the leg to be swung on its hinge into and out of the socket in a plane substantially parallel to the side member of the frame.

As shown in dotted lines in Figs. 2 and 4, the hinge member for the leg has one of its leaves 14 riveted to the supporting member 5 and its other leaf 15 fastened by screws 16 to the leg. The pivot 17 of the hinge is located close to the upper end of the leg. The hinge is positioned in the open side of the socket or channel member and spaced from the opposite wall 10 thereof in such manner that the leg will be forced snugly against this opposite wall 10 as the leg approaches its completely open position. The walls 10' of the socket extend beyond the leg when the leg is in the socket and these extended portions have slots 18 which are adapted to be engaged by a locking lever 19, carried by the leg. The locking lever is pivoted at 20 on the same side of the leg as the hinge is located, and, as is adapted to be swung about its pivot Fig. 3 after the leg has been swung into the socket to engage the slots 18 and lock the leg in position. The lever is formed with oppositely disposed notches adjacent its ends so that the ends of the lever will properly engage in the slots 18. The edges 21 of these notches are slightly angled to form cams which operate to draw the side walls 10' toward each other and clamp the leg between them. By turning the locking lever on its pivot into the dotted position shown in Fig. 3, the leg will be released so that it may be folded. The locking lever has an extended finger piece 22 by which it may be conveniently handled.

Referring more particularly to Fig. 4 it will be observed that the socket members are spaced inwardly from the frame B a sufficient distance to provide room for the lower ends of the legs mounted at the opposite corners. The leg when folded from the opposite corner extends practically to the frame member B. This makes it possible to obtain the maximum length of leg which can be folded within the frame.

It will be obvious to those skilled in the art that my invention may be embodied in other types of tables, and in fact other furniture, without departing from the spirit and scope of the invention and I desire it to be so understood.

I claim:

1. The combination of a table frame, a leg

supporting member secured only to said frame at the corner thereof, a leg, means hinging said leg on said supporting member whereby said leg may be swung substantially parallel with the frame, and means mounted on said supporting member for embracing the upper end portion of the leg when the leg is swung on its hinge to open position for holding the leg in rigid relation to the supporting member.

2. The combination of a rectangular table top frame, a leg, a supporting member carried by the frame, means hinging the leg on the supporting member to permit the leg to swing to open and closed position, and a socket member mounted on the frame adjacent the hinging means into which the leg is inserted when it is swung to open position.

3. The combination of a table frame, a supporting member carried by the frame, a channel member rigidly mounted on the supporting member adjacent the corner of the table frame, and having its open side facing in a direction substantially parallel with one side of the frame, a leg, means hinging the leg to said supporting member adjacent said channel member to permit the leg to swing into and out of engagement with said channel member.

4. The combination of a table frame, a supporting member carried by the frame, a channel member rigidly mounted on the supporting member adjacent the corner of the table frame and having its open side facing in a direction substantially parallel with one side of the frame, a leg, means hinging the leg to the supporting member to permit the leg to swing into and out of engagement with said channel member, and means for locking the leg in said channel member.

5. The combination of a rectangular table frame, a leg supporting member secured to the inside corner of the frame, a leg, a hinge having one leaf thereof secured to said supporting member and the other leaf thereof secured to the leg to permit said leg to swing substantially parallel with the frame, brace members mounted on said supporting member in position to be engaged by the upper portion of the leg when the leg is swung to open position for bracing the leg against movement laterally or transversely of its pivotal axis.

6. The combination of a rectangular table frame, a leg supporting plate secured to the inside corner of the frame, a leg, a hinge having one leaf thereof secured to said supporting plate and the other leaf thereof secured to the leg to permit said leg to swing substantially parallel with one side of the frame, brace members mounted on said supporting member in position to be engaged by the upper portion of the leg when the leg is swung to open position for bracing the leg against movement laterally or transversely of its pivotal axis.

pivotal axis, and a locking member carried by said leg for locking it in engagement with said brace members.

7. The combination of a rectangular table frame having a top board thereon, a plate positioned adjacent to and parallel with the under surface of said top board, flanges on said plate, means securing said flanges to the frame at the inside corner thereof, a socket member fastened to said plate with its longitudinal axis substantially at right angles to the plate, and having an open side facing in a direction substantially parallel with one side of said frame, a leg, a hinge having one leaf thereof secured to said plate and the other leaf thereof secured to said leg whereby said leg will be hinged at the open side of the socket member to swing into engagement with said socket member, and a lock for holding the leg in said socket member.

8. The combination of a rectangular table frame having a top board thereon, a plate positioned adjacent to and parallel with the under surface of said top board, flanges on said plate, means securing said flanges to the frame at the inside corner thereof, a socket member fastened to said plate with its longitudinal axis substantially at right angles to the plate, and having an open side facing in a direction substantially parallel with one side of said frame, a leg, a hinge having one leaf thereof secured to said plate and the other leaf thereof secured to said leg whereby said leg will be hinged at the open side of the socket member to swing into engagement with said socket member, and means for drawing the walls of said socket into clamping engagement with the leg when the leg is in the socket.
